US0D1097057S

(12) **United States Design Patent** (10) **Patent No.:** **US D1,097,057 S**
(45) **Date of Patent:** **** Oct. 7, 2025**

(54) **URINAL AND TOILET DEODORIZER WITH SURFACE ORNAMENTATION**

(71) Applicant: **Alex Girsh**, San Francisco, CA (US)

(72) Inventor: **Alex Girsh**, San Francisco, CA (US)

(**) Term: **15 Years**

(21) Appl. No.: **29/938,986**

(22) Filed: **Apr. 24, 2024**

(51) LOC (15) Cl. **23-01**

(52) U.S. Cl.

USPC **D23/208**

(57) **CLAIM**

The ornamental design for a urinal and toilet deodorizer with surface ornamentation, as shown and described.

DESCRIPTION

FIG. 1 is a top perspective view of a urinal and toilet deodorizer with surface ornamentation, showing my new design;

FIG. 2 is a front elevation view thereof;

FIG. 3 is a top plan view thereof;

FIG. 4 is a bottom plan view thereof;

FIG. 5 is a rear elevation view thereof; and,

FIG. 6 is a right-side elevation view thereof, the left-side elevation view being a mirror image thereof.

1 Claim, 4 Drawing Sheets
